UNITED STATES PATENT OFFICE.

GEORGE W. RENTON, OF BROOKLYN, NEW YORK, ASSIGNOR TO HIND STEEL & WIRE WORKS INC., OF NEW YORK, N. Y., A CORPORATION OF NEW YORK.

CLAW-HAMMER.

1,103,380.

Specification of Letters Patent. Patented July 14, 1914.

Application filed September 14, 1912. Serial No. 720,432.

To all whom it may concern:

Be it known that I, GEORGE W. RENTON, a citizen of the United States, residing at Brooklyn, in the county of Kings and State 5 of New York, have invented certain new and useful Improvements in Claw-Hammers; and I do hereby declare the following to be a full, clear, and exact description of the invention, such as will enable 10 others skilled in the art to which it appertains to make and use the same.

This invention is an improvement in claw hammers and is intended to provide a claw hammer of the usual type with means for 15 holding and driving a nail in places normally out of reach of a user.

An object of the invention is to provide a hammer of this type with a lug formed on the socket portion thereof, which lug 20 coöperates with the jaws of the hammer in holding a nail in position preparatory to driving same while permitting a release by direct backward movement of the hammer.

A further object of this invention is to 25 provide a lug of such form on the socket portion of a claw hammer so as to permit hammers with such lugs to be made by the usual process of drop-forging.

A further object of this invention is to 30 provide a hammer of this type with a lug formed on a socket which lug is tapered to permit free draft from a die and which lug may subsequently be notched as by a milling machine or shaper.

35 Further objects will be apparent from the following specification, appended claim and drawings, in which,

Figure 1 is a perspective view of the head of a hammer made in accordance with my 40 invention, Fig. 2 is a side elevation thereof showing one of the claws broken away, and, Fig. 3 is a sectional view thereof as on the line 3—3 of Fig. 2 showing the lug in elevation.

45 My invention resides in forming a lug on a socket of a hammer to engage the head of a nail and to assist the same in being held preparatory to driving.

Referring to the drawings 10 indicates the 50 head of the hammer provided with the usual claws 11 and socket 12. A lug 13 is formed

on the socket 12 under the jaws 11 and this lug is formed so as to taper and permit the hammer to be made in the usual style of drop-forging. The upper portion of the 55 lug is removed so as to form a shoulder 14 and a recess to receive the head of a nail as shown clearly in Fig. 2 of the drawings and the cutaway portion may be such as to present a rounded or sharp cornered recess 60 to receive the head of the nail.

In using the hammer for the use provided for by this invention, the nail is gripped by the shank sufficiently distant from the head to permit application with one hand and 65 the head is placed in the recessed portion formed by cutting away the lug 13 so that the head bears against the shoulder 14 when the shank is swung up and jammed between the claws of the hammer whereupon the nail 70 will be temporarily held until that portion extending beyond the claws is driven into place. Then by simply raising the hammer, it may be removed from the nail when the hammer can be turned around and used 75 in the ordinary fashion.

I am aware that various modifications may be made within the scope of this invention and I do not restrict myself to the identical form shown which is submitted for 80 illustrative purposes only.

Having thus described my invention, I claim:

A hammer embodying a socket portion having externally tapered sides and having a 85 bifurcation forming claws, said bifurcation stopping short of the socket portion; and a nail-head support formed upon the side of the socket portion next the claws, said support presenting a head-engaging upper surface substantially perpendicular to the tapered side of the socket portion and providing such structure that a nail head will engage directly against the outer wall of the socket portion. 90

95 In testimony whereof I affix my signature in presence of two witnesses.

GEORGE W. RENTON.

Witnesses:

HUGO MOCK,
GEORGE T. THOM.
